ELEVATOR BRAKE

Application filed March 16, 1928. Serial No. 95,152.

The principal object of this invention is, to increase the operating efficiency of high speed elevators by providing means separate from the arresting and holding brake which 5 will effectively slow down the movement of the elevator car to facilitate the making of accurate landings and reduce the stress on the ordinary brake.

The principal feature of the invention consists in the arrangement in connection with an elevator driving mechanism, of a supplementary braking device which will apply the maximum torque to the driving shaft when the elevator is in motion and gradually 15 reduce the torque as the speed of the mechanism decreases.

In the drawings, Figure 1 is a plan view of an elevator driving unit equipped with our improved braking device.

20 Figure 2 is a side elevational view in part mid-section.

Figure 3 is a transverse section on the line 3—3 of Figure 1 showing a portion of the hydraulic brake casing broken away.

25 In the operation of electrically driven high speed elevators with a single speed drive, the ordinary friction brake is subjected to very heavy stresses and it is difficult to effect accurate landings.

30 This invention has been devised to relieve the stress on the ordinary braking apparatus by exerting a retarding torque which will effectively slow down the operation of the mechanism prior to the application of the 35 stopping brake thus effecting a positive low speed from which accurate landings with smooth stops may be made.

In the accompanying drawings, the assembly illustrated is that of a standard type 40 of drive having the cable sheave 1 operated by a worm on the motor shaft 2.

A standard friction brake 3 is applied to the motor shaft, being electrically governed from the control mechanism in the car in 45 the usual manner.

The supplementary brake herein illustrated consists of a drum 4 rotatably mounted upon the shaft 2 and enclosing a rotor member 5 which is keyed to the motor shaft.

50 The rotor is provided with a plurality of

radial arms 6 preferably arranged in pairs and between these arms are arranged a plurality of radial arms 7 secured to and extending inwardly from the drum 4.

The periphery of the drum 4 rotates between the brake shoes 8 which are of the same type as applied to the brake 3.

This drum 4 is filled with oil or other suitable fluid and when the brake shoes 8 are out of engagement with the drum 4, said 60 drum rotates with the rotor and the shaft.

Immediately upon the application of the brakes 8 to grip the drum 4 and retard its rotation a resistance ensues between the radial arms 6 and 7 through the fluid medium 65 within the drum causing a reacting torque between the rotor and the drum which varies in direct relation to their relative speed, developing the maximum torque at the maximum motor speed with the drum at rest. 70

It will be understood of course that the construction of the rotor and the enclosing drum may be varied very considerably as may also various other features of construction without departing from the essential 75 feature of the invention.

When the elevator is being operated at high speed both the special hydraulic brake herein described and the friction brake are released and the drum 4 will acquire a speed 80 slightly less than the motor speed. The slip between the drum and rotor is just sufficient to develop torque enough to overcome bearing friction and windage of the member 4.

When it is desired to bring the elevator to 85 a stop the shoes 8 of the brake 4 are first applied and as soon as the drum is brought to rest the maximum kinetic energy of the moving mechanism is opposed to the resistance of the drum with its impeding vanes 90 retarding the movement of the fluid in the drum. The maximum torque is then developed and the speed of the mechanism decreases. The retardation decreases until such a speed is reached that the torque developed between the rotor and the drum is just sufficient to balance the net torque due to the motor and load. The arresting brake may be applied at any desirable period in the slowing down of the mechanism but by reason of 95 100

the initial slow down the stop will be quite smooth and as the stress on the arresting brake is light an accurate stop may be made.

With a slow-down type of brake such as described, it is possible to operate the elevator at a slow speed, such as for inching at landings. To utilize the device in this manner the usual friction brake is released and power is applied to the motor with the drum 4 held from rotation. The ultimate speed of the motor and therefore the elevator is predetermined at a limited low value by the resistance of the fluid within the drum.

It will be readily understood that a retarding brake such as described will be extremely applicable to elevator control as the kinetic energy of the elevator movement varies as the square of the speed and the torque of the hydraulic brake also varies as the square 20 of the speed.

What we claim as our invention is:

1. In an elevator brake, the combination with the means for driving an elevator operating mechanism in both directions and an 25 arresting brake therefor, of a supplementary brake applied to said mechanism adapted to develop a torque in either direction of rotation which diminishes as the speed of the elevator mechanism decreases.

2. In an elevator brake, the combination with the means for driving an elevator operating mechanism in both directions and an arresting brake therefor, of a mechanically controlled fluid-impeded supplementary 35 braking means adapted when controlled to automatically oppose the movement of said elevator operating mechanism in either direction with an intensity relative to the speed of travel of said elevator to de-celerate the 40 same independent of the arresting brake.

3. In an elevator brake, the combination with the elevator driving mechanism and a mechanical brake therefor, of a supplementary brake member adapted to normally rotate with said driving mechanism in either direction, fluid means interposed between said driving means and said supplementary brake member and normally effecting a driving connection between the two to rotate the 50 supplementary brake member with the driving means, and means for arresting the normal rotation of said supplementary brake member to effect a retarding action on said driving mechanism through the fluid means interposed therebetween.

4. In an elevator brake, the combination with the means for driving an elevator mechanism in both directions and an arresting 60 brake, of a rotor operatively connected with the driving mechanism, a member adapted to normally rotate freely with said rotor in either direction, means for arresting the movement of the latter rotative member, and 65 means for effecting a retarding influence on

the rotor through the arresting of said latter rotative member.

5. In an elevator brake, the combination with the motor shaft driven in both directions and a friction brake thereon, of a rotor 70 fixed to the shaft and having radial vanes, a drum rotatably mounted on the shaft and enclosing said rotor and being normally free to rotate therewith in the same direction, said drum having radial vanes arranged adjacent 75 to the radial vanes of the rotor, a fluid medium enclosed in said drum, and braking means for arresting the drum against its normal rotation with the shaft.
